DOUBLE COMPARTMENT WALL OVEN

Henry Honer, Los Angeles, Calif., assignor to Western Stove Company, Inc., Culver City, Calif., a corporation of California

Application October 1, 1956, Serial No. 43,171

Term of patent 14 years

(Cl. D81—4)

FIG. 2.

FIG. 1.

FIG. 3.

FIG. 4.

I claim:

The ornamental design for a double compartment wall oven, substantially as shown.
